L. STEINBERGER
COLUMN STRAIN INSULATOR

Filed Dec. 10, 1918

UNITED STATES PATENT OFFICE.

LOUIS STEINBERGER, OF BROOKLYN, NEW YORK.

COLUMN-STRAIN INSULATOR.

Application filed December 10, 1918. Serial No. 266,051.

To all whom it may concern:

Be it known that I, LOUIS STEINBERGER, a citizen of the United States, and a resident of the borough of Brooklyn, county of Kings, and State of New York, have invented certain new and useful Improvements in Column-Strain Insulators, of which the following is a specification.

This invention relates to a column strain insulator of the rod type and to improved terminals therefor.

One of the objects of the invention is to provide a column strain insulator having at each end a bell shaped terminal secured thereto, each terminal provided with a flaring skirt portion which extends outside the insulator at both ends and which project towards each other.

Another object of the invention is to provide such an insulator with bell shaped terminals so constructed as to be adjustably mounted upon the ends of the insulator to assume various positions with respect to the stress distributors which are permanently embedded in the ends of the insulator in the axial line thereof.

Another object is to provide such an insulator with adjustable bell shaped terminals, as described, and permanently fixed stress distributor members situated within the insulator body which, in combination with the bell shaped terminals, act to redistribute the dielectric stresses and strains.

Other objects will appear from the subjoined specification and claims.

Referring to the drawings:

Fig. 1 is a vertical section of an insulator embodying my invention.

Fig. 2 is a section on line 2—2 of Fig. 1. In the drawings in which the same reference character indicates the same part in the several views:

10 represents the body of insulating material of rod type, and it is provided on the surface thereof with a series of alternate ridges 11 and grooves 12, as shown, to increase its surface area. This rod may be made of any suitable insulating material, but I prefer to use for this purpose that insulating material well known in the art as electrose.

The rod of insulating material may be formed in any suitable manner, as by molding it into the shape shown, and when so formed there is molded into each end in the

axial line of the body, two members 20 and 21 which serve as stress distributors. Each of these members is provided at one end with a globular formation, as at 22 and 23 and the shanks 24 and 25 which project out from the body of the insulating material at each end are screw-threaded as at 26 and 27. Fitting over the screw-threaded ends of each of these shanks are bell shaped terminals 30 and 31, the skirt portions or flanges of which extend towards each other when in the inner positions a distance which is substantially one-third of the length of the insulator body. The outer edges of the skirt portions of these bell shaped terminals are beaded as at 50 and 51. Screw-threaded holes 32 and 33 are provided at the centers of the bases of the bell shaped members to engage respectively with the screw-threaded shanks of the projecting portions of the stress distributors so as to fit closely upon the respective ends of the insulator body.

Securing eyelets 40 and 41 are provided with screw-threaded cavities 42 and 43 in the shanks thereof which fit over the ends of the shanks 24 and 25 of the stress distributors so that the bell shaped members may be held rigidly against the respective ends of the insulator in one position, or may be adjusted at any suitable distance away from these ends, as clearly shown in dotted lines at the left of Fig. 1.

From the above described construction it will be seen that the bell shaped portions may be adjusted inwardly or outwardly so as to each cover substantially from one-third to one-quarter of the length of the insulator body and the outer beaded edges of the bell shaped terminals may have varying relations as to distance with the globular heads of the permanently embedded stress distributors 20 and 21 which are molded into the ends of the insulator rod during the process of manufacture.

The bell shaped cup portion being flared in substantially the form shown and being entirely on the outside of the insulating material, it is to be observed that in the event the line receives a stroke of lightning or a very high frequency impulse, the tendency would be to break down the air surrounding the insulator rather than the insulator itself.

The adjustability of the bell shaped portions with respect to the embedded stress

distributors regulates the redistribution of the dielectric stresses and strains within the insulator body.

By adjusting the position of the bell shaped members 30 and 31, the insulating unit may be adjusted for use on the primary or secondary circuit of an alternating current system of different potentials. When used on the secondary or lower potential circuit the bells 30 and 31 are adjusted to an air space or spark gap having a safe electric value higher than the potential of the circuit being insulated. The same, or a similar, insulator is applicable to the high potential circuit of the system by removing the bells and permitting the internal flux distributing or stress distributing members to operate.

Moreover, when an alternating potential is applied between the end terminals or a series of insulating units, the capacity of each unit may be graded by an adjustment of the position of the bell shaped external stress distributing members to provide a uniform distribution of the potential among the units. Thus those units nearest the line would have the bells in closest position to thereby increase its capacity while the unit next the ground would have its bells removed. Through the above invention, therefore, it is possible to obtain a wide adjustment in the characteristics and capabilities of a single unit to adapt it to different requirements, thereby avoiding the necessity of making and using a large number of units of different sizes and types. Moreover, a more gradual and finer adjustment of these properties is obtained than is possible with a limited number of units of fixed characteristics.

As changes of construction could be made within the scope of my invention, it is intended that all matter contained in the above description or shown in the accompanying drawings shall be interpreted as illustrative and not in a limiting sense.

Having now described my invention, what I claim as new and desire to secure by Letters Patent is:

1. In a device of the kind described, an insulator body, members forming stress distributors molded within its ends, the molded-in portions of the stress distributors being provided with globular shaped ends, the outwardly extending portions thereof being screw-threaded, bell shaped terminals

one at each end of the insulator body, the skirts of which surround the body of insulating material and the base portions of each being provided with means for engagement with the screw-threaded portions of the stress distributors, and fastening members fitting the screw-threaded portions of the stress distributors constructed to respectively engage the base portions of the bell shaped terminals.

2. In a device of the kind described, a body of insulating material, members embedded in the ends thereof, said members being provided with globular shaped ends situated in the axial line of the insulator body, portions of said members extending outwardly from the body, bell shaped terminals adjustably mounted upon said outwardly extending portions, and fastening means on said extending portions also operating to lock the terminals in place.

3. In a device of the kind described, a body of insulating material, members embedded in the ends thereof, said members being provided with globular shaped ends and being situated in the axial line of the insulator body, portions of said members extending outwardly from the body, bell shaped terminals adjustably mounted upon said outwardly extending portions, fastening members also adjustably mounted upon said outwardly extending portions and co-acting with the bases of the bell shaped terminals to lock the same in their respective adjusted positions.

4. In a device of the kind described, a body of insulating material, members provided with rounded ends forming stress distributors, one secured to each end of the insulator body, bell shaped arcing terminals adjustably mounted at each end of said body, the skirt portions of the terminals flaring outwardly from the body of insulating material and extending towards each other and means for jointly securing the bell shaped terminals in their adjusted positions and the device in place when installed.

In witness whereof, I have hereunto set my hand at the borough of Manhattan, city and State of New York, this fifth day of December, 1918.

LOUIS STEINBERGER.

In presence of—

ZITA M. GRAHAM.
